FLEX PUMP

Anthony C. Mamo, Des Plaines, Ill., assignor to Berg-Warner Corporation, Chicago, Ill., a corporation of Illinois

Filed Dec. 26, 1962, Ser. No. 247,057

14 Claims. (Cl. 103—123)

The present invention relates to a rotary pump and more particularly to a pump of this type wherein the rotor comprises a generally elliptical bearing.

Generally speaking, the elliptical bearing at its major axis provides lobes which are comparable to the vanes in a conventional type vane pump. This elliptical bearing may also be termed a lobed bearing, which may be provided with one or a multiplicity of lobes. The outer race or member of the elliptical bearing is nonelastic and flexible, and the major axis of the elliptical bearing is of a geometry such that the outer race will make contact with the inner periphery of a cavity at two opposing areas. As the rotor turns the inner race rolls on the rollers of the bearing thereby causing the outer race, at its lobe areas, to contact the inner periphery of the housing in a progressive movement around its periphery as herein-after more fully explained.

It is therefore an important object of the present invention to provide an improved rotary pump wherein the driven member of the rotor moves at a substantially lower velocity than the drive member.

It is also an important object of the present invention to provide an improved rotary pump which is hydraulically and mechanically balanced and wherein the frictional losses are greatly reduced.

It is another important object of the present invention to provide an improved positive displacement pump employing a lobed bearing.

The invention consists of the novel construction, arrangements and devices to be hereinafter described and claimed for carrying out the above stated objects and such other objects as will be apparent from the following description of preferred forms of the invention, illustrated with reference to the accompanying drawings, wherein:

FIGURE 1 is an elevational view of a rotary pump according to the present invention with the end plate removed showing the components therein;

FIGURE 2 is a cross section taken on line 2—2 of FIGURE 1;

FIGURE 3 is a cross section taken on line 3—3 of FIGURE 1;

FIGURE 4 is a cross section taken on line 4—4 of FIGURE 1;

FIGURE 5 is a cross section fragmentary view of the bearing and rotor within the housing showing a fluid sealing means;

FIGURE 6 is a fragmentary view taken on line 6—6 of FIGURE 5;

FIGURE 7 is a fragmentary view showing a modification of the rotor, FIGURE 1, wherein a segment of the rotor is removed at the minor diameter instead of the major diameter;

FIGURE 8 is a fragmentary view showing a modified form of the housing in FIGURE 1, comprising a flexible ring within the inner periphery of the housing;

FIGURE 9 is a sectional view in the direction indicated by line 9—9 of FIGURE 8; and

FIGURE 10 is a fragmentary elevational view of a modified form of the present invention with the end plate removed.

Like characters of reference designate like parts on the several views.

Referring now to FIGURE 1, numeral 10 designates a

2

suitable housing having a cylindrical cavity 11 therein. A drive shaft 12 is centrally journaled within the cylindrical cavity 11 and has a generally elliptical driving cam, or lobed rotor 13 connected thereto by means of a pin 14. A roller bearing 15 comprising flexible outer and inner races 16 and 17, respectively, having rollers 18 therebetween, is force mounted over the elliptical rotor 13 thereby becoming generally elliptical in shape. The major axis of the outer race 16 provides lobes or contact areas 19 and 20 which are in fluid sealing engagement with the inner periphery or peripheral wall 21 of the cylindrical cavity 11. The minor axis of the elliptical bearing 15 provides working areas 22 and 23 between the outer race 16 and the inner periphery 21 of the cylindrical cavity 11.

The generally elliptical rotor 13 has flattened areas 24 and 25 at the outer ends of the lobes. These flattened areas are provided so as to eliminate the necessity for maintaining a close dimensional control of the bearing 15 and the cylindrical cavity 11. This is so, because with segments removed from the major axis of the rotor 13, which produce the flattened areas 24 and 25, the flexibility of the bearing 15 will accommodate itself with respect to tolerances.

Vanес 26 and 27 operable in slots 28 and 29, respectively, are provided at opposite ends of the housing 10. The outer ends of the vanes 26 and 27 are provided with cylindrical heads 30 and 31, respectively, operable within bores 32 and 33, respectively, which extend coaxially with the slots 28 and 29. Within the cylindrical bores 32 and 33, springs 34 and 35, respectively, are biased between the cylindrical heads 30 and 31 and plates 36 and 37, respectively, which are secured to the outer ends of the housing by two sets of bolts 38 and 39. A suction port 40 and a pressure port 41 which are in communication with the cylindrical cavity 11 are positioned on opposite sides of the vane 26 and comparable suction and pressure ports 42 and 43, respectively, are positioned on opposite sides of the vane 27.

The pressure ports 41 and 43 may be provided with a generally U-shaped flat flexible spring 44 the ends of which extend into the cylindrical cavity 11.

Referring now to FIGURE 2, the housing 10 is provided with an end plate 45, fastened thereto by bolts 46, whereby the cylindrical cavity 11 is enclosed. The end plate 45 is provided with an annular recess 47 housing an annular pressure plate 48 having an annular protrusion 49 at its inner face thereby providing a pair of annular chambers 50 and 51 within the annular recess 47. The end plate 45 is also provided with a port 52 in fluid communication between the annular chambers 49 and 50, and the pressure port 41 by means of a conduit 53 whereby pressure is provided which urges the annular pressure plate 48 against the adjacent face of the roller bearing 15 which, in turn, causes the opposite face of the bearing 15 to move into fluid sealing engagement with the side wall 54 of the cylindrical cavity 11. In order to prevent fluid loss the annular pressure plate 48 is provided with fluid seals 55 and 56, such as O rings, at its inner and outer peripheries. Spacer washers 57 and 58 mounted on the drive shaft 12 are provided on opposite faces of the rotor 13 and are held from rotational movement by right angle segments 59 and 60, respectively, engaging recess 61 and 62, respectively, in side wall 54 and the end plate 45, respectively.

A U-shaped segmented ring 63, FIGURE 5, which encompasses the roller bearing 15 may be provided for more effective sealing against fluid loss. In FIGURE 6, segments 64 of the U-shaped segmented ring 63, are shown in a side elevational view.

A modification with respect to the vanes 26 and 27 is

shown in FIGURE 7. This modification of the vanes and their associated components, comprises positioning them at an acute angle and in a direction against rotational movement of the rotor 13 which virtually eliminates the sliding movement between the vanes and the outer race 16.

A modification of the cylindrical cavity 11 as shown in FIGURE 8 is another means of eliminating the necessity for maintaining close dimensional control with respect to the bearing 15, which comprises an annular yieldable wall 65 spaced from the inner periphery of the cylindrical cavity 11 by protrusions 66 and 67 thereon one each opposite the vane 26. The annular yieldable wall 65 is of a width equal to that of the cylindrical cavity 11 except at the area of the vane where a widened area 68 is provided having a rectangular opening 69 therethrough to accommodate the vane 26 and the suction and pressure ports 40 and 41, respectively. In order to accommodate the widened area 68, recesses 70 and 71 are provided at the inner faces of the cylindrical cavity 11 and the end plate 45.

The opposite portion of the annular yieldable wall 65 and the adjacent walls of the cylindrical cavity 11 and the annular pressure plate 48 are similarly fashioned.

A modified form of the invention, FIGURE 10, utilizes a journal bearing 72 comprising an elliptical yieldable journal 73 and a flexible bearing part 74 mounted over a generally rectangular rotor 75 having cam shaped ends or lobes 76 and 77.

In operation, the rotor 13 which is moving counterclockwise as indicated by the arrow, causes the outer race 16, which is in contact with the inner periphery of the cylindrical cavity 11 at areas at both ends of its major axis, to progressively contact the inner periphery of the cylindrical cavity in very limited fluid sealing engagement which causes the fluid in the working areas 22 and 23, forward of the vanes 26 and 27, respectively, to move into the pressure ports 41 and 43, respectively. Simultaneously, the working areas 22 and 23 that are on the opposite sides of the vanes 26 and 27, respectively, are being provided with fluid from the suction ports 40 and 42, respectively, which provides fluid for the succeeding pumping impulses. It is, therefore, apparent that with two pressure ports and two suction ports two pumping impulses are provided with each revolution of the rotor 13.

It is to be understood that a flex pump according to the present invention would be operable with but one pressure port and one suction port, but this would produce an unbalance.

It should also be noted that with the use of the elliptical bearing 15 according to the present invention the outer race 16 has a very low r.p.m. with respect to the input. Actually, its sliding velocity is reduced by approximately 90 percent at the sides and nearly 100% at the outer periphery for the reason that the outer race 16 is required to slide only to the extent of the differential between the inner periphery of the cylindrical cavity 11 and the outer periphery of race 16.

In the interest of maximum efficiency, it is recognized that port sizes should be as large as possible. However, if the port size is beyond a certain minimum, a point will be reached where intercommunication between suction and pressure ports will occur for a small fraction of time. This, however, can be eliminated by the use of the U-shaped flat flexible spring 44 which will substantially eliminate the intercommunication referred to because of the contacts between the ends of the spring with the outer race 16 as indicated by the dotted line in FIGURE 1.

In operation the modified form, FIGURE 10, is similar operationally, the difference residing in the substitution of a journal bearing for a roller bearing or a ball bearing, not shown, it being understood that a ball bearing may be used without departing from the spirit of the present invention.

With the use of the journal bearing 72 the generally rectangular rotor 75 may consist of two parts 75a and

75b mounted over a reduced diameter 77 of the drive shaft 12. The reduced diameter 77 is provided with flat surfaces as shown, against which the rotor parts 75a and 75b rest. Manifestly, when rotative force is applied to the drive shaft 12, the parts 75a and 75b are urged against the inner periphery of the journal bearing 72 for effective sealing against fluid loss. Also the necessity for close tolerances in manufacturing the rotor 75 is avoided. The pin 14, of course, is not required.

While this invention has been described in connection with certain specific embodiments thereof, it is to be understood that is by way of illustration and not by way of limitation and the scope of this invention is defined solely by the appended claims which should be construed as broadly as the prior art will permit.

I claim:

1. A rotary pump comprising; a casing having a bore therein defining a cylindrical cavity provided with a peripheral wall and side walls; a multiple lobed rotor journaled in said casing coaxially within said cylindrical cavity; a bearing having an inner member and a nonelastic flexible outer member mounted over said multiple lobed rotor thereby providing multiple lobes on said bearing equal in number to the number of lobes on said multiple lobed rotor, said multiple lobes on said bearing extending radially to a degree such as to be in fluid sealing contact with said peripheral wall thus providing working areas in the area encompassed by said multiple lobes on said bearing, the adjacent portion of said inner periphery, the adjacent portion of the outer face of said outer nonelastic flexible member and the adjacent portions of said side walls, the said outer nonelastic flexible member being of a width to be in fluid sealing contact with said side walls, the said inner member being in rotatable engagement with said rotor which causes said outer nonelastic flexible member to flex as said inner member rotates with respect to said outer nonelastic flexible member rolling progressively on said peripheral wall with scant sliding thereon; a vane reciprocally mounted in said casing extending through said peripheral wall towards said outer nonelastic flexible member and in fluid sealing engagement therewith; a suction port in said peripheral wall on one side of said vane in fluid communication with said cylindrical cavity; and a pressure port in said peripheral wall on the opposite side of said vane in fluid communication with said cylindrical cavity.

2. A rotary pump according to claim 1 wherein the said nonelastic flexible outer member is encompassed by a U-shaped ring having radially inwardly extending segments to thereby provide more effective sealing against fluid loss, the said nonelastic flexible outer member being reduced in width to accommodate said U-shaped ring with its inwardly extending segments.

3. A rotary pump according to claim 1 wherein the said exhaust port is provided with a U-shaped flat flexible spring of a width substantially that of said cavity, the far end of which extends beyond the said peripheral wall to thereby prevent fluid intercommunication between the said pressure and suction ports when they exceed the maximum size permissible to prevent intercommunication.

4. A rotary pump according to claim 1 wherein the said peripheral wall comprises a semi-rigid annular ring thereby providing extensibility of said inner peripheral wall to accommodate lack of adequate tolerance at the major axis of the bearing in assembling.

5. A rotary pump according to claim 1 wherein one of said side walls comprises an annular pressure plate provided with fluid means for urging said pressure plate into sealing engagement with the said nonelastic flexible outer member.

6. A rotary pump according to claim 1 wherein the said inner member comprises a yieldable journal.

7. A rotary pump according to claim 1 wherein the said vane is positioned at an acute angle and in a direction against rotational movement of the said rotor

thereby virtually eliminating the sliding movement between the said vane and the said nonelastic flexible outer member.

8. A rotary pump according to claim 1 comprising a ball bearing having a nonelastic flexible outer member.

9. A rotary pump according to claim 1 wherein the said multiple lobed rotor is elliptical in shape and wherein a second vane corresponding to said vane and substantially opposite thereof, and a second suction port and a second pressure port comparable to said suction and pressure ports respectively are provided on opposite sides of said second vane.

10. A rotary pump according to claim 9 wherein said inner member is elliptical in shape to correspond to the elliptical shape of said rotor and wherein a comparable second vane, a comparable second suction port, and a comparable second pressure port are provided in the casing substantially opposite the said vane, the said suction and pressure ports respectively.

11. A rotary pump according to claim 9 wherein a said inner member is semi-rigid thereby conforming to the shape of said elliptical rotor when mounted thereover.

12. A rotary pump according to claim 9 wherein the said elliptical rotor is provided with flattened ends at its major diameter to thereby accommodate the mounting of said bearing in the event of a minus tolerance.

13. A rotary pump according to claim 9 wherein the said elliptical rotor is provided with flattened ends at its minor diameter to thereby accommodate the mounting of said bearing over said motor in the event of a minus tolerance.

14. A rotary pump comprising: a casing provided with a bore therein defining a cylindrical cavity having a peripheral wall and side walls at right angles thereto; a multiple lobed rotor journaled in said casing coaxially within said cylindrical cavity; a roller bearing comprising an outer nonelastic flexible member and an inner member mounted over said multiple lobed rotor,

the said outer nonelastic flexible member thereby having multiple lobes which extend outwardly to a degree such as to be in fluid sealing contact with said peripheral wall, thus providing working areas in the area encompassed by said multiple lobes on said outer nonelastic flexible member, the adjacent portion of said peripheral wall, the adjacent portion of the outer face of said outer nonelastic flexible member and the adjacent portion of said side walls, the said outer nonelastic flexible member being of a width to be in fluid sealing contact with said side walls, the said inner member being in rotatable engagement with said rotor which causes said outer flexible member to roll on the rollers of said roller bearing and flex as it progresses on said peripheral wall with scant sliding thereon; and a vane reciprocally mounted in said casing extending through said peripheral wall toward said outer flexible member and in fluid sealing engagement therewith; a suction port in said peripheral wall on one side of said vane in fluid communication with said cylindrical cavity; and a pressure port in said peripheral wall on the opposite side of said vane in fluid communication with said cylindrical cavity.
